CLAIM

The ornamental design for a hand torch, as shown and described.

DESCRIPTION

FIG. 1 is a top right perspective view of an embodiment of a hand torch showing our new design;

FIG. 2 is a top left perspective of the hand torch illustrated in FIG. 1;

FIG. 3 is a left side view of the hand torch illustrated in FIG. 1;

FIG. 4 is a front view of the hand torch illustrated in FIG. 1;

FIG. 5 is a right side view of the hand torch illustrated in FIG. 1;

FIG. 6 is a rear view of the hand torch illustrated in FIG. 1;

FIG. 7 is a top view of the hand torch illustrated in FIG. 1;

FIG. 8 is a bottom view of the hand torch illustrated in FIG. 1; and,

FIG. 9 is a perspective view of the hand torch in the direction of the arrows of line A-A illustrated in FIG. 6.

The broken lines in the drawings illustrate portions of the hand torch that form no part of the claimed design.

1 Claim, 8 Drawing Sheets
